DIRECTLY HEATED CATHODE STRUCTURE

Beverly D. Kumpfer, Spring Lake Heights, N. J.,
assignor to the United States of America as
represented by the Secretary of the Army

Application May 1, 1950, Serial No. 159,351

4 Claims. (Cl. 313—346)

(Granted under Title 35, U. S. Code (1952),
sec. 266)

1

The invention described herein may be manufactured and used by or for the Government for governmental purposes, without the payment to me of any royalty thereon.

This invention relates to improvements in cathode structures, and more particularly to directly-heated cathodes for embodiment in subminiature magnetrons.

In the conventional cathode structure, heat from a filament is transferred or conducted to a thermionically-active surface through an interposed layer of insulating material or through the wall of a metal cylinder on the outside surface of which thermionically-active material is deposited. These are known as indirectly-heated cathodes, examples of which are disclosed in Patent No. 2,014,787, issued September 17, 1935, to Smithells et al., and in Patent No. 2,194,678, issued March 26, 1940, to Sommers. Due to the fact that heat is imparted to the thermionically-active material indirectly, the thermal efficiency of the conventional, indirectly-heated cathodes is relatively low. The construction or fabrication of the indirectly-heated cathodes, furthermore, is such that it would be practically impossible to make them in very small sizes for embodiment in subminiature magnetrons, for example. Also, the cathode structures of the prior art have a relatively short life under severe operating conditions such as exist in subminiature magnetrons where high ruggedness and large emissive surface, in proportion to overall size, are required.

With the foregoing in mind, it is one of the objects of my invention to provide an improved cathode structure adapted particularly for use in subminiature magnetrons, and which in any case, has a longer effective life than the various cathode constructions of the prior art, under the same operating conditions.

Another object of my invention resides in the provision of an improved cathode structure which has advantages over those proposed heretofore in the way of higher thermal efficiency and greater ruggedness of construction.

Another object of my invention is the provision of an improved cathode structure for magnetrons which not only can stand up under the severe operating requirements of high ruggedness and high emissive rate in proportion to size, but which lends itself also to fabrication or manufacture in very small sizes such as are required for embodiment in subminiature magnetrons.

Other objects and advantages will hereinafter appear.

For the purpose of illustrating my invention,

2

an embodiment thereof is shown in the drawing, wherein:

Figure 1 is an enlarged, longitudinal sectional view of a cathode constructed and operating in accordance with my invention, the section being taken on the line 1—1 in Figure 3;

Figure 2 is a front, elevational view of Figure 1;
Figure 3 is a plan view of Figure 2; and

Figure 4 is a view similar to Figure 1, but on a reduced scale and showing a practical application of my invention.

For the purpose of simplification in disclosing my invention, the step-by-step operations in making or fabricating a cathode structure embodying the same, will first be explained with reference, particularly, to Figure 1. Alumina is first applied by spraying or dipping, to a support member in the form of a rod 10, after which the rod so coated is baked in an atmosphere of hydrogen to convert or change the alumina to a hard ceramic substance 11. The member or support rod 10 is thus characterized by the fact that the outside surface thereof is of insulating material. In one application of my invention such as is shown in Figure 4 and which has given satisfactory results in subminiature magnetrons, the rod 10 was of tungsten with an outside diameter of .007 inch, and its length was approximately .85 inch. Also, in this particular application the thickness or depth of the insulating layer or coating 11 was .003 inch, and it extended over substantially the entire length of rod 10, as shown in Figure 4.

The heater for my improved cathode is in the form of a wire wound about rod 10 to provide a filament 12. In the particular application of my invention referred to above, nickel wire having a diameter of two thousandths of an inch was used for the filament 12. In applying this wire to rod 10 to form the heater or filament 12, one end is first spot-welded to a protective nickel cap 14 fitted over the upper end of the rod and in electrical contact with the latter, as shown. This end of wire 12 may, however, be spot-welded directly to the upper end of rod 10, as represented at 15 in Figures 2 and 3. The filament wire 12 is then wound about rod 10 to make approximately two hundred fifty turns per linear inch. The respective adjacent turns of the helix thus formed are therefore spaced, for the specified gauge of wire used, approximately .002 inch. The other end of the wire is then spot-welded, as represented at 16, to a nickel sleeve 17 fitted onto the lower end of rod 10 and electrically-insulated from the latter by the ceramic coating 11.

To complete the assembly or fabrication, ther-

thermionically-active material 18 is applied by spraying or dipping, and as more clearly illustrated in Figure 1, serves the additional function of bonding the turns of wire 12 to the insulating ceramic coating 11 on the central, support rod 10. In Figures 1, 2 and 3 the thickness or depth of the emission coating 18 is shown as not quite covering completely the wire helix. In Fig. 4, the thickness or depth of the coating 18, which was composed of triple carbonates, was approximately .002 inch.

In the construction shown in Figure 4, a nickel sleeve 19 fitted over the assembly, imparts additional rigidity and strength at the junction of filament 12 with sleeve 17, and also protects the spot-weld connection between the latter two parts.

The sleeve 17 and the lower end of rod 10, both of which are disposed at one and the same end of my improved cathode structure, provide, respectively, terminal connections for current-supply to filament 12 from any suitable source such as a battery represented at 20. In the construction shown in Figure 4, parts 21 and 22 are spot-welded, respectively, to sleeve 17 and rod 10, and serve as terminals for more conveniently making connection to the battery 20 or other power-supply.

While my improved cathode structure has been described as being especially adapted for use in magnetrons, it may be used to equal advantage in any of the many different, present-day types of thermionic tubes. An important aspect of my invention resides in the novel construction, arrangement and dimensional relations of the respective parts to each other, all of which makes practical an otherwise extremely difficult cathode construction, results in a unit lending itself to reasonably easy manufacture in the very small sizes required for use in subminiature magnetrons, and has at the same time the essential operating characteristics and capabilities for prolonged use under the severe operating conditions imposed in magnetrons.

In some forms of cathode constructions embodying my invention, it may be more expedient to use for the filament 12 a metal in strip form, instead of the more conventional wire or circular form shown. There may be other alternatives such as using molybdenum instead of tungsten for the rod 10, and any other suitable materials in substitution for those specified for the respective parts.

While but one embodiment of my invention has been shown and described, it will be understood that various modifications such as in the size, shape and arrangement of the parts, may be made within the conception of those skilled in the art without departing from the spirit of my invention or the scope of the claims.

What is claimed is:

1. A directly heated cathode comprising an electrically conductive rod, insulating means disposed on the outside surface of said rod, a wire wound about the insulated rod so as to provide a filament, a cap disposed about one end of said rod and electrically connecting it to said filament wire, thermionically-active material intimately associated with and disposed between adjacent

turns of said wire along a given length of said insulated rod and bonding said filament wire thereto, first sleeve means disposed about the other end of said insulated rod and electrically connected to said filament wire, second sleeve means disposed about said first sleeve means as well as a portion of said filament, for providing protection for the junction of said filament and said first sleeve, and means disposed at said other end of said rod and electrically connected thereto and to said first sleeve, for supplying current to said filament.

2. A directly heated cathode assembly comprising a rigid inner conductor, a layer of insulating material bonded to the outer surface of said conductor, a wire wound about the insulated conductor so as to provide a filament, thermionically-active material disposed between adjacent turns of said filament bonding said filament to said insulated conductor, and a pair of current-supply terminals at one end of said assembly, one terminal being electrically connected to one end of said conductor and the other terminal being electrically connected to a like end of said wire, the other end of said wire being electrically connected to the other end of said conductor.

3. A directly heated cathode structure comprising a conductive member at least the outside surface of which is of insulating material, a heater in the form of a filament wound about said member, thermionically-active material disposed between adjacent turns of said filament along a given length of said member and bonding said filament thereto, a pair of terminals disposed at one and the same end of said structure and respectively in contact with said member and said heater for providing terminal connections for current-supply of said filament, and means electrically connecting said filament to said member at the ends thereof remote from the terminal connection end of said structure.

4. A directly heated cathode structure comprising a conductive rod, a layer of insulating material bonded to the outer surface of said rod, a wire wound about the insulated rod and in contact with said insulating material to provide a filament, thermionically-active material disposed between adjacent turns of said wire and extending radially outwardly beyond said wire along a given length of said rod bonding said filament to said insulating material, and a pair of terminal means disposed at a given end of said structure, said terminal means being respectively in electrical contact with said rod and said wire, and providing terminal connections for current-supply to said filament, said filament being electrically connected to said rod at the end of said cathode structure remote from the terminal connection end of said structure.

BEVERLY D. KUMPFER.
